ELECTRIC VALVE CIRCUITS

Burnice D. Bedford, Schenectady, N. Y., assignor
to General Electric Company, a corporation of
New York

Application June 12, 1944, Serial No. 539,941

12 Claims. (Cl. 315—262)

1

My invention relates to electric valve circuits and more particularly to control or excitation circuits for electric valves of the type employing an ionizing medium, such as a gas or a vapor.

In the control of electric valve apparatus including an ionizable medium such as a gas or vapor capable of supporting an arc discharge, one critical period in the operating cycle is the deionization period. This is particularly true when the valve apparatus is used as an inverter to convert direct current to alternating current. Grids have been suggested and used heretofore in both thyratrons and ignitrons to obtain accurate starting and rapid deionization in inverters. However, in the ignitron type of valve where the cathode spot is intended to be formed every half cycle an undesirable situation arises in the event the ignitor fails to fire or for some reason the cathode spot fails to form. If, under these conditions, the grid is made positive the residual ionization in the valve may form a cathode spot by bombardment on the side walls and other equally undesirable locations within the valve envelope.

It is an object of my invention to provide new and improved excitation and control circuits for electric valves.

It is another object of my invention to provide new and improved excitation and control circuits for a gas-discharge valve with a pool type cathode in which an ignition means is employed to control the starting of unidirectional current flow in each operating cycle.

It is a further object of my invention to provide new and improved excitation and control circuits for the ignitron type of valve which will overcome the difficulties above set forth.

In accordance with the illustrated embodiment of my invention, I employ a modifying or coupling means between a holding or auxiliary anode circuit of the electric valve and the grid excitation circuit of the valve whereby the excitation circuit cannot be energized sufficiently to effect conduction in the valve in the absence of proper electron emission from the cathode such as the formation of a cathode spot in the regular and intended manner.

My invention will be better understood from the following description taken in connection with the accompanying drawing and its scope will be pointed out in the appended claims.

The single figure of the accompanying drawing illustrates one embodiment of my invention as applied to an electric valve conversion system.

In the drawing, I have illustrated one form

of my invention as embodied in an electric valve conversion system comprising two valve groups 1 and 2 which may be taken as representative of a system adapted for converting from direct current to alternating current, or vice versa, such as might be utilized at one end of a high voltage direct current transmission line or dual conversion type frequency converter unit. There are six valves in each group arranged in a three-phase double-way circuit. Valve group 1 is connected through a transformer 3 to a circuit 4 which may be taken to represent either a supply circuit or a receiving circuit. Valve group 2 is connected similarly to valve group 1 through a transformer 5 to the circuit 4.

Since the particular details of the arrangement of the valves form no part of my present invention, it is believed sufficient for an understanding of the invention to describe in detail the excitation and control circuits for one valve pair of valve group 1. The valves of this pair are rendered conductive 180 electrical degrees apart and are identified as 6 and 7. The type of valve selected for purposes of illustration is known in the art as a pentode ignitron by reason of the use of three grids in addition to the other two principal electrodes. Valves 6 and 7 are each provided with an anode 8, a first electrode or grid 9 which acts as an intermediate anode, a control electrode or grid 10 which determines the time of starting and reduces the deionization period at the end of conduction, and an outer control electrode or grid 11 which acts in a dual capacity to pick up the arc at the beginning of conduction and to shield the other grids and anode structure from residual ionization after conduction. In addition, each of the valves 6 and 7 is provided with a mercury pool cathode and two ignitors 13 and 14 although only one need be used at one time. Above the surface of the mercury are arranged auxiliary anodes or holding anodes 15 and 16. The auxiliary anode 15 may function primarily to maintain the cathode spot for low values of anode current and the auxiliary anode 16 is utilized in accordance with my invention to prevent the possible uncontrolled formation of cathode spots through its coupling with the grid excitation circuit about to be described.

The power supply for both the ignitor circuits and the grid circuits may conveniently be obtained, as illustrated, from a single auxiliary transformer 17 through a multiple-phase shifting device 18 in order to control the respective pairs of valves. A satisfactory type of ignitor circuit is of the so-called magnetic type and

a particularly satisfactory species of this type is the illustrated form which has been described and claimed in application Serial No. 413,232, of A. H. Mittag, filed October 1, 1941, and assigned to the assignee of the present application. The ignitor circuit 19 is energized from a circuit 20 of the phase shifter 18 of appropriate phase and transmits unidirectional impulses of current of peaked wave form to the ignitor members 13 and 14 of the valves 6 and 7 and causes a cathode spot to be established in these valves alternately during intervals of time displaced substantially 180 electrical degrees. The circuit 19 is connected to the respective ignitor circuits through an insulating transformer 21 having a primary winding 22 and a pair of secondary windings 23 and 24. The insulating transformer is used to transform the ignitor peaks up to the high potential level of the valves. The primary winding 22 is energized from the circuit 20 through a nonlinear reactance or firing reactor 25 and a shunt connected capacitance 26, which elements in combination cause a peak of voltage to be generated across the secondary windings of transformer 21. These impulses of voltage occur twice during each cycle of voltage of circuit 20 at times determined by the saturation of the firing reactor 25 and are transmitted to the respective ignitor circuits through the secondary windings 23 and 24. Since a pair of ignitors are used in each valve, one terminal of the winding 24 is connected to the cathode circuit of valve 6 and the other terminal is connected to the midtap of a current dividing reactor 27 having its outer terminals connected to ignitors 13 and 14 through unidirectional conducting devices 28 and 29. The secondary winding 23 is similarly connected to the ignitors 13 and 14 of valve 8 through a midtapped current dividing reactor 30 and unidirectional conducting devices 28 and 29. The circuit 19 also includes a linear reactance 31 connected between the circuit 20 and the capacitor 26 which serves to prevent discharge of the capacitance to the supply circuit upon saturation of the firing reactor 25, and which also serves to limit the amount of current derived from the supply circuit at the time capacitance 26 discharges through transformer winding 22. A further reactor 32 is connected in shunt to the circuit input terminals of the firing reactor 25 and firing capacitor 26. This reactor is designed to operate somewhat above saturation and is preferably provided with a core material to saturate sharply so that it will tend to hold substantially constant voltage over wide limits of variation in the supply voltage. The circuit 19 is also provided with an additional shunt connected compensating circuit comprising a capacitance 33 connected in series with a linear reactor 34 across the supply circuit and a series connected linear reactance 35 for maintaining the voltage applied to the firing capacitance 26 substantially constant for a predetermined range of phase displacements of the voltage of the firing circuit with respect to the supply circuit voltage.

Since the firing circuit 19 furnishes current to the ignitors for only a relatively few degrees after the ignitor fires, a holding anode 15 is utilized to maintain the cathode spot for substantially the remainder of the half cycle of positive anode voltage and is conveniently energized from the source of excitation for the grid excitation circuit 36. The circuit 36 includes a transformer 37, which may be referred to as the grid excitation transformer. Transformer 37 is provided

with a primary winding 38 and a pair of insulating secondary windings 39 and 40 which isolate the grid circuit from ground potential. The holding anode 15 is energized from a transformer 41 having a primary winding 42 connected to be energized from the secondary winding 39 of the grid excitation transformer 37. The secondary winding 43 of the holding anode transformer 41 has one terminal thereof connected to the cathode of valve 6 and the other terminal connected to holding anode 15 through a current limiting resistor 44 and a unidirectional conducting device 45.

Negative bias for the control grid 10 and shield grid 11 is supplied by a bi-phase, double-way rectifier 46 which is energized through a transformer 47 also connected to be energized from the secondary winding 39 of the grid transformer. A capacitor 48 and resistance network 49 comprising resistors 49' and 49'' serve to regulate the grid bias voltage. The resistors 49' and 49'' preferably should have a nonlinear volt-ampere characteristic, such as the resistance material having the trade-mark "Thyrite," which is disclosed and claimed in United States Letters Patent No. 1,822,742, granted September 8, 1931, upon an application of Karl B. McEachron.

In the event the valve groups 1 and 2 are operated as phase commutated inverters, accurate firing is essential, since a small error will mean a much greater change in the deionization angle. In order to obtain the desired accuracy of firing a peaking transformer 50 is utilized to introduce a positive pulse of voltage in circuit with control and shield grids 10 and 11. The peaker voltage must necessarily rise higher than the negative bias voltage and the rise should be so rapid that negligible error is introduced if one valve requires a greater positive grid voltage than another. The peaker transformer 50 is provided with a primary winding 51, which is connected to be energized from the grid transformer secondary winding 39, and a secondary winding 52. In accordance with my invention, I make the firing of the grid dependent upon the controlled formation of a cathode spot. One means of accomplishing this interlocking or coupling which has shown satisfactory operation in practice is to connect the secondary winding 52 of the peaker transformer 50 in a circuit through the auxiliary or holding anode 16 and provide in series relation with this circuit a coupling impedance or, as illustrated, a transformer 53. The transformer 53 is provided with a primary winding 54 connected in series relation with the auxiliary anode 16 and a secondary winding 55. Thus when this holding anode circuit is completed by the arc path through auxiliary anode 16, the peaker impulse will appear in the winding 55 and be impressed upon the grids 10 and 11. A resistor 56 having a nonlinear volt-ampere characteristic, such as that specified for resistances 49' and 49'', may be connected across the winding 54 as a voltage protective means. The winding 54 is connected to the auxiliary anode 16 through an adjustable linear resistance 57 and a unidirectional conductive device 57'. The resistor 57 prevents undue variations in the duration of the peaks irrespective of variations in the impedances of the circuits of auxiliary anode 16 and grids 10 and 11. The resistor 57 is made adjustable to adjust the duration of the peaking impulse. The secondary winding 55 is provided with an intermediate tap 58 which is connected through a current limiting and adjusting resistor 59 to the

point of maximum negative potential of the negative bias resistor network 49''. The lower terminal of secondary winding 55 is connected through a nonlinear resistance 60, preferably of the type specified for resistances 49' and 49'', and to a point intermediate the resistors 49' and 49''. The upper terminal of transformer 53 is connected directly to the control grid 10 and through a nonlinear resistor 61 to the shield grid 11. This resistor 61 is used to insure that the control grid 10 will fire after the shield grid. The path for the peaking impulse impressed upon grids 10 and 11 may be traced from the cathode 12 of valve 6 through the upper resistor 49', through grid firing resistor 60, through transformer secondary winding 55 to grids 10 and 11.

It will be noted that the peaking impulses through the primary winding 54 of the coupling transformer 53 are unidirectional impulses which tend to cause an accumulative direct current saturation of the core of this transformer. In order to avoid this accumulative saturation, I provide a circuit to circulate a current in opposition to the magnetizing current of the transformer 53 which is derived from the current in the circuit of the secondary winding 55. This circuit includes part of the principal grid firing circuit from the junction of resistors 49' and 49'', through resistor 60, through the lower portion of secondary winding 55, out of the tap 58, through the linear resistor 59 to the most negative point of the voltage divider 49 which is the lower terminal of resistor 49''. This circuit becomes effective to circulate the reverse current through winding 55 upon the termination of the peak of current in primary winding 54. Since the auxiliary anode 16 is energized by a peaking impulse, the arc established by such peak between anode 16 and the cathode terminates prior to the arc at the regular holding anode 15 which is energized from a substantially sinusoidal source of voltage. Thus when the peak terminates in winding 54 the lower terminal of winding 55 is more positive than the intermediate terminal 58 so that a current is caused to flow through a portion of the winding 55 from the voltage across resistor 49''. This current is in a direction such as to magnetize the core in a direction opposite to the magnetization effected by the current impulses in transformer winding 54. A resistor 62 50 of the nonlinear type, previously referred to, is connected across the cathode grid circuit as a general voltage protective means for the grid circuits.

The grids 10 and 11 are preferably connected to the cathode through the capacitors 63 and 64, respectively, in order to make the grid potential follow the absolute cathode potential during sudden changes in its potential particularly during the commutation period when the valves are 60 functioning as an inverter.

The grid 9, above referred to as an intermediate anode, is connected through a resistor 65 to an intermediate point of resistors 66 and 67 which are connected in series relation across the anode and cathode of valve 6 and serve to divide the potential gradients between the anode and cathode during nonconducting periods.

The general sequence of operation of the ignition and excitation circuits of the electric valve system is substantially as follows: The particular ignitor circuit shown generates a positive peak of current in each half cycle of applied voltage upon discharge of the capacitor 26 through the firing reactor 25 and the firing transformer 21.

The peak on one-half cycle causes current to flow through the ignitors 13 and 14 of valve 6 to establish a cathode spot and the peak on the following half cycle causes current to flow 180 degrees later through the ignitors 13 and 14 of valve 7. Upon establishment of the cathode spot, in for example valve 6, the current in the auxiliary anodes 15 starts to flow and thereby maintains the cathode spot after the ignitor peak has subsided for the desired remaining portion of the cycle. As soon as the auxiliary anode 16 is rendered conductive upon firing of the grid peaker transformer 50, the circuit through the secondary winding 52 of the peaker transformer is completed and the peaker voltage is introduced into the circuit of grids 10 and 11 with a steeply rising positive wave sufficient to render the grids positive and establish conduction in the valve. Both grids must be made positive to establish conduction.

Now if the cathode spot is not formed and the electron emission is insufficient at the desired time and in the intended manner and the grids were made positive in the absence of a cathode spot or insufficient electron emission from the cathode, electrons are drawn from the space below the grids and ionization follows so that voltage gradients may become sufficient to form a cathode spot on the side walls or many other undesirable points within the valve envelope. However, in the illustrated embodiment of my invention, the grids cannot be made positive unless the auxiliary anode 16 is conducting since in the absence of a conducting path in the secondary winding 52 of the peaker transformer, the peaker impulse is not transmitted to the grids and the grids are maintained at a negative potential.

While I have shown and described a particular embodiment of my invention, it will be obvious to those skilled in the art that various changes and modifications may be made without departing from my invention, and I, therefore, aim in the appended claims to cover all such changes and modifications as fall within the true spirit and scope of my invention.

What I claim as new and desire to secure by Letters Patent of the United States is:

1. In combination, an electric discharge device of the type employing an ionizable medium and comprising an anode, a cathode and a control electrode, means for initiating electron emission at said cathode, an excitation circuit for said control electrode, a source of excitation voltage, means for establishing a path for electron emission from said cathode, and means including said path of electron emission from said cathode for impressing said source of voltage upon said excitation circuit for determining the instant of conduction between said anode and cathode.

2. In combination, an electron discharge device of the type employing an ionizable medium and comprising an anode, a cathode and a control electrode, means for periodically establishing electron emission at said cathode, an excitation circuit for said control electrode, a source of excitation voltage, means interposed between said cathode and said control electrode for collecting electron emission from said cathode, and electric circuit means including the path of electron emission between said cathode and said last-mentioned means for introducing said source of voltage in said excitation circuit for determining the instant of conduction between said anode and cathode.

3. In combination, an electron discharge device

of the type employing an ionizable medium and comprising an anode, a cathode, an auxiliary electrode and a control electrode, means for establishing a region of electron emission at said cathode, means including said auxiliary electrode for establishing current conduction between said region of electron emission and said auxiliary electrode, and means including a coupling means between said auxiliary electrode and said control electrode for effecting energization of said control electrode only upon initiation of current flow between said auxiliary electrode and said cathode.

4. In combination, a pair of circuits one of which is an alternating current circuit, electric translating apparatus connected between said circuits and comprising an electric discharge device of the type employing an ionizable medium capable of supporting an arc discharge and including an anode, a cathode, an arc initiating member associated with said cathode, an auxiliary electrode associated with said cathode and a control electrode interposed between said anode and said cathode for determining the instant of conduction between said anode and cathode, means for controlling said arc initiating member to establish an ignition spot on said cathode, means for establishing a current path between said auxiliary electrode and said cathode upon establishment of said ignition spot, an excitation circuit for said control electrode, and means including the current path between said auxiliary electrode and said cathode for introducing a voltage in said excitation circuit of said control electrode to effect conduction between said anode and said cathode.

5. In combination, an alternating current circuit, a direct current circuit, electric translating apparatus connected between said circuits and comprising an electric discharge device of the type employing an ionizable medium capable of supporting an arc discharge and including an anode, a cathode, an ignitor control member associated with said cathode, an auxiliary electrode associated with said cathode, and a control electrode interposed between said anode and said cathode, means connected to said ignitor control member for causing ionization of said medium and for establishing an ignition spot on said cathode, an energizing circuit connected to said auxiliary electrode for establishing current flow therein only upon establishment of said ignition spot on said cathode, an excitation circuit for said control electrode, and means interlocking the excitation circuit of said auxiliary electrode and the excitation circuit of said control electrode for establishing a potential on said control electrode sufficient to cause conduction between said anode and cathode only upon establishment of current flow in the excitation circuit of said auxiliary electrode.

6. In combination, an alternating current circuit, a direct current circuit, electric translating apparatus connected between said circuits and comprising an electric discharge device of the type employing an ionizable medium capable of supporting an arc discharge and including an anode, a cathode, an ignitor control member associated with said cathode, an auxiliary anode, and a control electrode interposed between said anode and said cathode, a source of excitation, means connected to said source for supplying current to said ignitor control member for ionizing said medium and for establishing an ignition spot on said cathode, means connected to said source for energizing said auxiliary anode

in dependence upon the flow of current between said auxiliary anode and said ignition spot, and means including the current path between said auxiliary anode and said ignition spot for establishing a potential on said control electrode sufficient to cause conduction between said anode and cathode.

7. In combination, an alternating current circuit, a direct current circuit, electric translating apparatus connected between said circuit and comprising an electric discharge device of the type employing an ionizable medium capable of supporting an arc discharge and including an anode, a cathode, an immersion-ignitor control member associated with said cathode, an auxiliary anode, and a control electrode circuit, an excitation source, means connected to said source for transmitting impulses of energizing current to said immersion-ignitor control member for ionizing said medium and for establishing an ignition spot on said cathode, means connected to said source and including a winding for producing a voltage of peaked wave form, means connecting said winding in a series circuit with said auxiliary anode, and inductive means interconnecting said series circuit and said control electrode circuit.

8. In combination, an alternating current circuit, a direct current circuit, electric translating apparatus connected between said circuits and comprising an electric discharge device of the type employing an ionizable medium capable of supporting an arc discharge and including an anode, a liquid type cathode, an ignitor control member associated with said cathode, a holding anode and a grid control electrode interposed between said holding anode and said anode, a source of excitation, excitation means connected to said source for effecting the formation of a cathode spot on the surface of said liquid cathode, an excitation circuit for said holding anode, a peaking transformer having a primary winding and a secondary winding, said primary winding being connected to said source of excitation and said secondary winding being connected in series relation with said holding anode, circuit means for connecting said control electrode to said source of excitation, and means for coupling the circuit of said holding anode and the circuit of said control electrode.

9. In combination, an alternating current circuit, a direct current circuit, electric translating apparatus connected between said circuits and comprising an electric discharge device of the type employing an ionizable medium capable of supporting an arc discharge and including an anode, a cathode, an ignitor control member associated with said cathode, a holding anode, and a grid control electrode interposed between said holding anode and said anode, a source of excitation, means interconnecting said source and said ignitor for effecting the formation of an ignition spot on said cathode, an excitation circuit interconnecting said source and said holding anode, a transformer for producing periodic voltages of peaked wave form and having a primary winding and a secondary winding, said primary winding being connected to said source of excitation and said secondary winding being connected in series relation with said holding anode for introducing in the circuit of said holding anode periodic voltages of peaked wave form upon conduction of current between said holding anode and said ignition spot, transformer coupling means for interconnecting the circuit of said

holding anode and the circuit of said control electrode, means connected to said source of excitation for establishing a negative bias potential, and means for connecting said negative bias potential in the circuit of said control electrode.

10. In combination, an alternating current circuit, a direct current circuit, electric translating apparatus connected between said circuits and comprising an electric discharge device of the type employing an ionizable medium capable of supporting an arc discharge and including an anode, a cathode, an ignitor control member associated with said cathode, a holding anode and a grid control electrode interposed between said holding anode and said anode, a source of excitation, means interconnecting said source and said ignitor for effecting the formation of an ignition spot on said cathode, an excitation circuit interconnecting said source and said holding anode, means including a peaking transformer having a secondary winding connected in a series circuit with said holding anode, a unidirectional conductive device connected in circuit with said holding anode, a coupling transformer comprising a primary winding and a secondary winding having a pair of end terminals and an intermediate terminal, said primary winding being connected in series relation with the secondary winding of said peaking transformer to said holding anode, the secondary winding of said coupling transformer being connected in series relation with said control electrode, means connected to said source of excitation and including a rectifier and a pair of resistors for producing a unidirectional voltage across said pair of resistors, circuit means for connecting one of said resistors in circuit with said control electrode to impress thereon a negative bias potential, and means connecting the other of said resistors to one of said end terminals and said intermediate terminals for causing a unidirectional current flow between said last mentioned terminals of such a value and polarity as to prevent accumulative saturation on said coupling transformer due to the unidirectional current impulses on said holding anode circuit.

11. In combination, an alternating current circuit, an electric discharge device connected to said alternating current circuit of the type employing an ionizable medium capable of supporting an arc discharge and including an anode, a cathode, an arc initiating member, an auxiliary electrode disposed in the region of said cathode and a control electrode interposed between said anode and cathode for determining the instant of conduction of said discharge device, means for

controlling said arc initiating member to establish a source of ionization on said cathode, a source of voltage, means for connecting said source of voltage in circuit with said auxiliary electrode so as to impress unidirectional impulses of voltage upon said auxiliary electrode, an inductive means having a core structure and one winding connected in series relation with said auxiliary electrode and a second winding connected in series relation with said control electrode, and means for reversing the magnetization of said core subsequent to the termination of each of said unidirectional voltage impulses.

12. In combination, an alternating current circuit, a direct current circuit, an electric discharge device connected between said circuits of the type employing an ionizable medium capable of supporting an arc discharge and including an anode, a cathode, an ignitor control member associated with said cathode, an auxiliary anode disposed in the region of said cathode, and a control electrode interposed between said anode and cathode for determining the instant of conduction of said discharge device, means for establishing an ignition spot on said cathode, means including a peaking transformer having a secondary winding connected in series circuit with said holding anode, a unidirectional conductive device connected in circuit with said holding anode, a coupling transformer comprising a primary winding and a secondary winding having a pair of end terminals and an intermediate terminal, said primary winding being connected in series relation with the secondary winding of said peaking transformer to said holding anode, the secondary winding of said coupling transformer being connected in series relation with said control electrode, a source of unidirectional current, and means for connecting said source to one of said end terminals and to said intermediate terminal for causing a unidirectional current flow between said last mentioned terminals of such a value and polarity as to prevent accumulative saturation in said coupling transformer due to the unidirectional current impulses in said holding anode circuit.
